UNITED STATES PATENT OFFICE

HENRY G. LYKKEN, OF MINNEAPOLIS, MINNESOTA

DEVICE FOR OPERATING UPON FLUIDAL MATTER

Application filed July 2, 1925. Serial No. 41,168.

The present invention relates to devices for producing and handling pulverized or fluidal matter.

Among the objects of the invention is to provide a novel separator or classifier for separating given fine particles of matter and conveying the separated particles to a place of use, such as to a combustion chamber of a furnace or similar device where the material used is powdered or pulverized fuel. The material is preferably first crushed and pulverized and the pulverized material is preferably cast or projected into a stream through which a fluid, such as air, may be drawn to carry part of the projected material from the projected stream thereof, in a state of suspension to a separating point, the air acting as a medium of conveyance and suspension, and also as a supporter of combustion at the point of use.

To effect classifying separation of the fines from the coarser particles or the fine particles that are wet or laden with moisture, the invention comprehends the feeding of the stream of air and suspended particles tangentially or similarly into a classifying or separating chamber so that the mass may be given a centrifugal action, a whirl, eddy or vortex action, or a cyclonic action, so that the finer particles, not laden with moisture, may be carried with the air stream to the place of use, preferably by way of a blower or a exhaust fan, or similar draft means creating a drawing action on the air and suspended particles in the pulverizing and separating mechanisms.

The classifier or separator, in a specific form, has an outer chamber or casing connected with a pulverizing device and having an end wall having an outlet connection to the exhaust fan, this chamber acting as a passage for the material and air. Within this chamber is preferably provided an inner chamber specifically in the form of a hollow cone being open at both ends, the larger open end of which being so located that the flow of the material and air may be from the outer chamber into the inner chamber through such opening. This opening is preferably variable either by moving

the inner chamber to or from an end of the outer chamber so as to decrease or increase such opening, or by interposing a movable sleeve between the open end of the inner chamber and the space of the outer chamber, such that the raising of the sleeve will decrease the opening and the lowering of the sleeve will increase the opening.

Between the open larger end of the inner chamber and the walls of the outer chamber, is preferably provided a set or series of spaced vanes or blades so located that the stream and air proceeding toward the inner chamber will pass between and among these vanes or blades and be directed tangentially into the inner chamber through the larger open end thereof so as to produce the centrifugal action, whirl, eddy, vortex or cyclonic action, or the like, above mentioned. The degree of this action will be controlled by the size of the opening or passage at the open end of the inner chamber and the degree of draft action effected by the feeding means or blower operating to convey the separated particles and air to the place of use.

The classifier or separator may also have, preferably, at its lower and smaller end a discharge outlet through which the coarser particles or the fine particles laden with moisture, may be discharged back into the outer chamber for return to the pulverizing device or for further suspension of the fine particles in the upwardly moving stream of air and suspended material, these particles being returned again to the separating chamber for separation. The discharge opening is preferably tapered and of a size to hold sufficient material to prevent a back-flow of air therein and also for permitting an aspiration at the discharge end of this discharged opening by reason of the stream of air and suspended material blowing or flowing past such discharged end. Beneath this discharge opening is preferably provided a spreader for aiding and spreading the discharged material over a large area for a facile aspiration of the material as it is discharged. In this way, when the particles are being discharged, the upward

flow of air will catch up some of the fine particles and carry the same back to the separating chamber, these particles, in the meanwhile having part or all of its moisture extracted so that they may be separated in the separating chamber and carried to the place of use along with the other separated particles.

The invention also may comprehend a novel pulverizing means having means for projecting a stream of pulverized material against impact members preferably arranged in different points so that the cast or projected material may be widely dispersed and thoroughly mixed. These impact members may be in the form of cross bars and arranged relatively proximate so as to restrict the area of the passages therebetween and increase the velocity of air passing upwardly between them and through the stream of material being projected thereagainst and dispersed thereby.

The air or other supporter of combustion is preferably admitted in the lower part of the pulverizing device and drawn upwardly through the spaces between these bars and through the mass of material being projected against these bars and dispersed by them. The stream of air will then carry the particles of the material in suspension to the separating means, expansion of the fluidal mass occurring in the outer and inner chambers of the separator, to permit the return of the coarse particles, in addition to the separation effected by the action in the inner chamber.

Other objects, advantages and capabilities are comprehended by the invention as will later appear and are inherently possessed by the invention.

Referring to the drawings illustrating the invention,

Fig. 1 is a vertical transverse sectional view taken through a device constructed in accordance with the invention;

Fig. 2 is a horizontal sectional view taken through the separator of the device; and,

Fig. 3 is a fragmentary vertical sectional view taken through a modified form of the separator;

Referring now more in detail to the figures of the drawings the embodiment selected to illustrate the invention is shown as comprising a pulverizing device having a casing 1 in which is rotatably mounted a pulverizing rotor 2 driven by a shaft 3 and carrying pulverizing arms 4 cooperating with a corrugated pulverizing surface 5 and material 6 located in the base of the chamber 1 so that a mulling action occurs between the material carried between the hammers 4 and the surface of the material 6 located in the bottom of the pulverizer.

At the upper part of the pulverizer is located a hopper, in which the material, such

as coal 8 may be placed for crushing by a crushing roll 9 operating upon the material and in cooperation with a plate 10 pivotally mounted upon a pivot 11 secured to the casing of the pulverizer. The plate 10 has secured to it an arm 12 carrying a weight 13 which may be adjusted on the arm 12 as desired. The plate 10 is held in a position with reference to the crushing roll so as to gauge the size of the material to be crushed. A supporting member 14 may be provided on the pulverizer so as to hold the arm 12 in proper position for the plate 10 to be in gauging position with reference to the crushing roll 9. The crushed material is then fed into a chamber 15 where the material is acted upon by a feeding roll 16. It is desired that the material be fed into the chamber 15 at a greater rate than the feeding roll feeds it therefrom into the chamber of the pulverizer. If the material increases in the chamber 15 at a greater rate, it will pile upwardly against a door 17 and be fed back into the hopper 7. If any piece be engaged by the feeding roll 16 of greater size than would be ordinarily permitted to pass, a release gate 18 normally held in place by spring 19 will yield to permit the passage of such piece. The material is fed by gravity into the chamber of the pulverizer and on the discharge side of the pulverizing rotor 2. If there are any hard and non-crushable pieces fed into the chamber, the hammers 4 will impact them at initial contact with sufficient force to cast them downwardly into the bottom of the chamber 1 and to imbed them in the fuel or other material without in any way carrying them around with the rotor, as clearly shown in Fig. 1 of the drawings.

The material being ground will be cast substantially horizontally against the impact members 20 and 21 preferably in the form of cast bars supported by suitable transverse members 22 and 23 secured to the side walls of the pulverizer.

At the opposite side of the pulverizer chamber is provided an air inlet passage 24 leading into the lower part of the pulverizing chamber. Beneath the passage 24 is also provided an opening or passage 25 through which the material accumulated in the bottom of the pulverizer may be withdrawn when it is desired to clean the same.

Above the space 26 in which the material may be cast by the rotor is connected an expansion chamber or outer casing 27 of a separating device. This casing has an end wall 28 from which leads an outlet connection 29 having a top plate 30, and a discharge opening 31 connected with a conduit leading to an exhaust fan (not shown) adapted to draw the material through the separator and to feed the same to a combustion chamber of a furnace or similar place.

of use. Within the outer chamber 27 is located an inner chamber 32 preferably of hollow cone shape having an opening 33 in its upper and larger end and a discharge opening 34 at its lower and smaller end. This chamber may be supported by means of a rod 35 secured to a spider 36 attached, in any suitable manner, to the side walls of the cone 32. The lower end of the rod 35 may 5 be also secured to a cone shaped member or spreader 37, the upper surface 38 of which converges with reference to the surface 39 of the discharge end of the cone. In this way the annular throat or discharge passage 34 is tapered as clearly shown in Fig. 1 of the drawings. The upper end of the rod 35 is threaded to receive a thumb nut 40 whereby the cone may be suspended in adjusted 10 position; a turning of the nut 40 being of utility to adjust the height of the cone as 20 desired.

Within the outer casing 27 at the upper end thereof is provided a circular series of vanes or blades 41 being secured in any 25 suitable manner at their inner ends 42 thereof to the inner wall of the casing 27 or to the upper end wall 28, as desired. These blades extend inwardly toward the upper 30 open end of the cone and in proximity thereto so that the upward flow of air and suspended particles passing into the spaces between the vanes may be projected inwardly in a tangential direction into the space over the cone 33 and into the same so as to produce a whirling or centrifugal action of the 35 mass of material and air. The cone 32 may be raised or lowered so as to vary the discharged openings between the blades and above the open end of the cone so as to intensify or retard the projection of the 40 material from the spaces between the blades into the cone. This may be also varied by the degree of draft created by the exhaust fan. As the mass is caused to act in the 45 form of a cyclone or eddy in the cone, the heavier particles will be carried toward the periphery or sidewalls of the cone 33 and will be carried downwardly through the discharge opening 32 thereof. Fine particles laden with moisture will also take the same 50 course as the coarse material. The fine and dry particles will be carried to the center with the air and will be drawn upwardly into the outlet 29 and discharge 31 to the exhaust fan which will convey the same to the combustion chamber.

The non-separated material proceeding to the lower end of the cone will accumulate 55 in the passage 34 and by reason of the tapered condition of the throat thereof, it will prevent a back-flow of air upwardly through this passage, and will also allow the gravitational movement of the particles through 60 the throat. As the particles pass over the

upper surface 38 of the spreader, and discharge into the space of the chamber 27, the upward flow of air and suspended particles will cause an aspiration at the opening of the throat 34 and will again carry up the 70 fine particles which have moisture, and will dry the particles in their recirculation through the blade spaces and to the cone. The air may be heated if desired. These particles may then be separated with the 75 other fine particles and be carried away for use. The heavier particles not carried upwardly, will return to the pulverizing chamber for repulverizing or regrinding.

The bars 20 and 21 are so located at different points in the path of discharge of the material from the hammers 4 so as to cause the material cast thereupon to be dispersed in various directions. The draft created by the fan will cause an inflow of air through the passage 24 into the lower part of the grinding chamber and upwardly through the path of the material projected by the rotor and the material dispersed by the bars 20 and 21. These bars may be of 80 large size and so spaced from each other as to cause restricted spaces between them whereby the velocity of the air in such spaces may be increased. The upward flow of the air will then carry the particles in 85 suspension to the separating chamber.

Additional bars 43 may be placed in the passage from the grinding chamber to the separating chamber 27 to aid in restricting the passages and effecting tortuous paths to cause an increase of velocity and dispersion effect of the upward flow of air and suspended material.

In Fig. 3 the classifying or separating device is similar to that described in connection with Figs. 1 and 2, but for the purpose of adjusting the discharge openings from the inter-vane spaces, a sleeve 44, preferably of cylindrical form, and located between the periphery of the cone 32 and the inner edges 45 of the vanes may be suspended by means of supporting rods 46 threaded at their upper ends to receive thumb nuts 47 which may be operated to raise or lower the sleeve 44 as desired. The rods 46 pass through suitable openings in the top wall 28 for exterior access for adjustment. In this connection the cone 32 may be adjusted as desired, but the adjustment may also be made by raising and lowering the sleeve 44.

The raising and lowering of either the cone or the sleeve will vary the size of the openings between the vanes through which the material and air passes, this mass passing with a whirling action into the upper portion of the cone. As the mass is caused to rotate in the form of a cyclone or eddy in the cone, the centrifugal action will cast the 130

heavier and coarser particles to the inclined walls of the cone and the finer particles will be carried upwardly and through the passage 29. The heavier and coarser particles will coast down to the opening 34 to be discharged into the passage of the chamber 27 for either reaspiration, as above explained, or for return to the chamber of the grinder or pulverizer for further reduction in size. 10 When the cone or sleeve 24 is lowered and greater openings are effected at the discharge of the vanes, a decrease in tangential velocity of the mass is effected and consequently there is a less tendency to throw the coarse material outwardly by centrifugal action, thus effecting a carrying of a greater amount of heavier and coarser material, or in other words, the material carried away by the air to the point of use is heavier and coarser than if the velocity were greater. 20 A raising of the cone or sleeve will increase the velocity of projection of the material and air into the cone and thus produce a greater throwing down of the heavier and coarser particles and the retaining or separating of finer particles to be carried away by the air stream to the point of use. Only a part of the fine material is thus carried away, the fine particles which are laden with moisture being carried down with the coarse particles and fed out of the lower end of the cone for reaspiration by the upward stream of air and material passing through the vanes and into the cone. In this way the 30 fineness of the material ultimately used may be controlled to a fine degree. The reaspiration of the fine particles laden with moisture, will effect an extraction of the moisture therefrom so that the fine particles will then 40 be separated in the cone with the other fine particles and be carried away for use. From the above it will be apparent that the separating device has a dual function, that of separating by centrifugal action and that 45 of reaspiration.

The group of rods 20, 21 and 43 may be regarded as a dash gate which may be varied by varying the sizes of the rods or the shape thereof to cause different degrees of dispersion of the materials.

While I have herein described and upon the drawings shown a few embodiments of the invention, it is to be understood that the invention is not limited thereto, but also comprehends other constructions, arrangements of parts, and details, without departing from the spirit thereof.

Having thus disclosed my invention, I claim:

60 1. In a separator for acting on fluidal material, an outer casing, an inverted hollow cone therein, tangential vanes secured to said outer casing and located between said casing and the larger end of said cone, whereby fluidal matter passing in among said vanes

will be directed by said vanes into a whirl in said cone.

2. In a separator for acting on fluidal material, an outer casing, an inverted hollow cone therein, tangential vanes secured to said outer casing and located between said casing and the larger end of said cone, whereby fluidal matter passing in among said vanes will be directed by said vanes into a whirl in said cone, said cone being vertically adjustable relative to said vanes.

3. In a separator for acting on fluidal material, an outer casing, an inverted hollow cone therein, spaced vanes surrounding the larger end of said cone and having their outer ends secured to the inner wall of said casing, said vanes being located to cause flow of the fluidal matter into said cone with a whirling action.

4. In a separator for acting on fluidal material, spaced inner and outer hollow chambers, a series of spaced vanes therebetween for affording a passage of the material among said vanes and for directing the material tangentially into said inner chamber to cause a centrifugal action of the material in said inner chamber, said vanes being secured to said outer chamber.

5. In a separator for acting on fluidal material, spaced inner and outer hollow chambers, a series of spaced vanes therebetween for affording a passage of the material among said vanes and for directing the material tangentially into said inner chamber to cause a centrifugal action of the material in said inner chamber, said vanes being secured to said outer chamber, and means for varying the relation of said inner chamber and said vanes for varying the discharge of the material from among said vanes into said inner chamber.

6. A separating device comprising an upright hollow chamber having an end wall, an inverted cone in said chamber and having its larger end spaced from the end and side walls of the chamber, spaced vanes between the larger end of said cone and said walls for providing passages from the interior of said chamber to the interior of said cone.

7. A separating device comprising an upright hollow chamber having an end wall, an inverted cone in said chamber and having its larger end spaced from the end and side walls of the chamber, spaced vanes between the larger end of said cone and said walls for providing passages from the interior of said chamber to the interior of said cone, a sleeve slidably located between said vanes and said cone for controlling the passages of material from said vanes into said cone.

8. In a device for operating on powdered material, a casing, a hollow cone in said casing, tangentially arranged vanes outside the cone and between it and the casing wall to which the vanes are fixed and means for

regulating the fineness and the quantity of the fine product by vertically adjusting a hollow cone disposed between tangentially arranged vanes fixed in the surrounding casing.

5 9. In a fuel device having pulverizing means, a separating means having inner and outer casings with tangentially disposed vanes between said casings, said inner casing having means for discharging the oversize and surplus material for repulverizing.

10 10. In a separating device, a chamber, a hollow cone therein, vanes surrounding the cone and located in the chamber, means for varying the relation of the cone and the vanes, a discharge means at the base of the cone and a spreader associated with said discharge means and adapted to discharge material in the path of the material moving through the chamber.

15 11. A separating chamber of the cyclonic type having means for directing material into a whirl into said chamber, and a tapered discharge outlet at the lower end of the chamber for the discharge of material accumulated therein and a tapered valve for controlling the discharge through said outlet.

20 12. A separating chamber of the cyclonic type having means for directing material into a whirl into said chamber, and a tapered discharge outlet at the lower end of the chamber for the discharge of material accumulated therein, and means associated 25 with said outlet whereby passage of material by said outlet will cause aspiration of the material in said outlet.

30 13. A separator comprising an outer chamber having an open lower end and being 35 provided with an outlet at its upper end, an inner chamber having an open upper end spaced from the upper end and the side of said outer chamber to provide a passage from said outer chamber to said inner chamber, tangentially located vanes between said inner chamber and the side of said outer chamber; for causing a flow of air and suspended particles of material to enter said inner chamber in a whirl whereby the finer particles may be separated and conveyed through said outlet, and a tapered valve for controlling the discharge through said outlet.

35 14. A separator comprising an outer chamber having an open lower end and being provided with an outlet at its upper end, an inner chamber having an open upper end spaced from the upper end and the side of said outer chamber to provide a passage 40 from said outer chamber to said inner chamber, tangentially located vanes in said passage between said inner and outer chambers for causing a flow of air and suspended particles of material to enter said inner chamber in a whirl whereby the finer par-

ticles may be separated and conveyed through said outlet, and means movable between said vanes and the open upper end of said inner chamber for varying the size of said passage to control the fineness of the 70 particles separated in said whirl.

15 15. A pulverizing device comprising a pulverizing chamber having an air inlet, a separator casing immediately above said pulverizing chamber and communicating therewith, said separating chamber having an air exhaust, so that an induced current of air may be maintained through both chambers, a rotatable pulverizer in said pulverizing chamber and positioned laterally 75 with respect to said separating chamber, so as to be located to one side of the path of travel of the induced air current, said pulverizer having means for discharging pulverized material into said air stream, means 80 in said separator chamber for separating the coarser particles from the finer particles of said material, and means within said separating chamber and located above said pulverizer for returning the remaining particles to said air current by gravity, so that 85 a supplemental separation of the said particles will be obtained.

16. In a fuel device, a separator having means for causing a stream of air to travel 90 upwardly therethrough, means for throwing pulverized fuel laterally into said air stream so that the fuel particles will be carried thereby, means for classifying the fuel particles while carried by said air stream so as 95 to remove the coarser particles, and means for again depositing said removed particles, and means for again depositing said removed particles directly into said air stream so that they are subjected to a second classification while travelling therewith.

17. A stoking device for pulverized fuel comprising a pulverizing chamber, a separator chamber immediately above said pulverizing chamber and communicating therewith, said separating chamber having an air exhaust so that an induced current of air may be maintained through both chambers, a pulverizing device in the pulverizing chamber positioned laterally with respect to the separating chamber so as to be located to one side of the path of travel of the induced air current, said pulverizer having means for discharging pulverized fuel into said air stream, means in the separating chamber for separating the finer particles of fuel from the coarser particles while being conveyed by said air stream, means for returning the coarser particles to be reground, and means for causing said reground particles to enter said air stream before regrinding so as to recover any lighter constituents which may be carried thereby.

18. In a stoking device for powdered fuel, means for pulverizing the fuel and dis-

charging the same laterally, a separator positioned laterally of and above the pulverizer and having an exhaust opening so that an induced current of air may be maintained through said stream of pulverized fuel, means for separating the finer constituents from the fuel conveyed by said air stream, means for controlling the fineness of the particles being separated, means for returning the coarser particles to be repulverized, and means for causing the returned particles to pass through said air stream so as to effect a supplemental separation.

In witness whereof, I hereunto subscribe
15 my name to this specification.
